MASKING APPARATUS FOR FINISHING ARTICLES OF MANUFACTURE

Harry Cohen, Galion, Ohio, assignor to The Perfection Steel Body Company, Galion, Ohio, a corporation

Application July 23, 1934, Serial No. 736,621

10 Claims. (Cl. 101—114)

This invention appertains to the art of masking or stenciling apparatus, such apparatus being used for the purpose of applying paint, lacquer or other finishes to articles of manufacture.

5 The present invention embodies an apparatus of the above type designed especially for the application of marbleized finishes, so to speak, to metal burial vaults, but the principle of construction of the apparatus of the invention is useful generally in order to apply finishes of different kinds to different types of articles.

In carrying out the invention, I contemplate the employment of suitable supporting means upon which the article to be finished may be carried in the painting or finish applying operation.

Associated with the supporting means are the masking devices proper, the same comprising largely a stationary combined back and top section, a movable combined top and front section and movable end sections. Associated with the combined top and front section are certain counterbalancing weight devices which facilitate the easy and ready lifting of said combined front 25 and top section when it is desired to place the article to be finished in the masking apparatus and remove it. The end sections are automatically movable to spread positions in order to afford ready access to the article to be finished 30 for purposes of its removal and for emplacing the same in the apparatus.

Additionally, I employ automatic operating parts by which when the article being finished has been placed in proper position in reference to the combined back and top section, upon lowering the combined front and top section the said automatic devices carried by the latter section will engage the end sections and cause the same to assume their operative closed positions, and 35 when the combined top and front section is elevated to assume an open position automatic spring mechanism will act upon the end sections and cause the same to spread or open to render it easy to remove the finished article.

40 A full understanding of my invention will be had upon reference to the accompanying drawings, in which:

Figure 1 is a perspective view of the complete apparatus with the parts in closed operative positions ready for the application of a finish to an article enclosed by the various sections of the masking device.

Figure 2 is a front view omitting the lifting cables, and frame means, for the counterbalance weights and illustrating the combined front and

top section elevated and the end sections spread apart as when the apparatus is ready to receive the burial vault or similar article to be treated for the purpose of applying the finish thereto.

Figure 3 is a view somewhat similar to Figure 2 but showing a burial vault disposed in position ready for the closing together of the several sections of the masking apparatus.

Figure 4 is an end perspective view showing the masking enclosure as when enclosing the burial vault to be finished, the lifting chains and cables broken away.

Figure 5 is an end perspective view of fragmentary nature looking somewhat from the front of the apparatus and illustrating the parts seen in Figure 4 a little more clearly.

Referring now to the drawings and specifically describing the invention, it will be noted that my apparatus includes two uprights 1 and 2 at the upper end of which are horizontal arms or beams 3. Suitable pulleys or sheaves are carried by said beams or arms 3 and cables 4 pass about said pulleys, each cable carrying at one end a weight 5 and being attached at its opposite end to one end of the combined front and top section of the masking enclosure, as shown at 6.

The masking enclosure consists of a housing made up of a plurality of sections, which for the purposes of this description will be designated the combined back and top section 7, the combined front and top section 8 and the end sections 9.

In general, the housing of the masking enclosure will conform to the shape of the article which is to be finished, and in the present instance, the said sections 7, 8 and 9 are formed with slot-like openings 10 of many different formations through which openings paint, lacquer, or other finishing material may be sprayed when the sections 7, 8 and 9 are in their closed positions, as illustrated in Figures 1, 3, 4 and 5.

In order that the wall structure of the parts 7, 8 and 9 may be strong notwithstanding the formation of slotted openings 10 therein as seen, it is contemplated to connect portions of these parts on opposite sides of the slotted openings by

means of stirrup or U-shaped members 11 which project outwardly from the outer surfaces of the members and enable the paint, lacquer, or other finishing material to be sprayed through the openings 10 the entire length of these openings.

The combined back and top section is supported in a stationary manner by means of vertical standards 12, and in order to support the burial vault or other article to be finished in proper position in the masking enclosure, suit-

able supporting rails 13 are employed and disposed in spaced relation to the base of said enclosure.

The end sections 9 of the masking enclosure 5 are hinged at their rear edges, as shown at 14, to the standards 12. Likewise, there are provided offstanding arms 15 on the end sections 9 adjacent to the upper hinges 14 and springs 16 are connected at one end with these arms and 10 at their opposite ends with the standards 12 and normally are under expansion tension when the end sections 9 are closed, as shown in Figures 1, 4 and 5.

In other words, the tendencies of the springs 15 16 by their normal set is to pull the sections 9 outwardly after the manner shown in Figure 2 and the said springs constitute automatic means for doing the above work.

The combined front and top section 8 of the 20 apparatus is equipped with laterally and downwardly inclined cam members 17 which constitute automatic devices for engagement with the end sections 9 and these members come into play upon the downward closing movement of the 25 section 8 for the purpose of engaging the parts 9 to force the same to closed positions, as illustrated in Figure 5.

With the construction of the invention set 30 forth as above noted, the operation of my apparatus is very simple. In the emplacing of a burial vault or other article of manufacture in the masking enclosure, the parts will be arranged as shown in Figure 2. The article to be 35 finished is then placed upon the base supporting rails 13, as shown in Figure 3. The operator then grasps the handle 18 which projects from the outer side of the section 8 and pushes down upon this section so as to carry it to the position of Figure 1. This operation is performed 40 with ease because of the use of the counterbalancing weights 5 which substantially counterbalance the weight of the section 8.

As the section 8 approaches its downward limit of movement, the automatic acting cam 45 members 17 engage with the upper edge portions of the end sections 9 and cause the end sections to close in toward the ends of the burial vault 19 as the section 8 reaches its operative closed position illustrated well in Figures 1, 4 and 5.

50 It is to be understood that my masking enclosure may be of different shapes, and while for the purpose of giving a marbleized finish by the stenciling actions of the parts 1, 8 and 9, I use a certain form and arrangement of the slotted openings 10, I wish it to be understood that I do not want to be limited in reference to the specific form of the masking enclosure parts, or the specific arrangement of the said openings 10 because these phases of my invention may be modified in 60 a manner obvious to those versed in the art.

Having thus described my invention, what I claim as new and desire to secure by Letters Patent of the United States, is:—

65 1. In masking apparatus of the class described, in combination, a masking enclosure comprising a rearmost section, end sections movably mounted upon said rearmost section, means normally holding the end sections in an open outward position, a frontward section movable in relation 70 to the rearmost section, and members carried by the frontward section engageable with the end sections in moving the frontward section to closed position, whereby to cause the end sections to close to operative positions about an article of manufacture at the same time that the

frontward section is caused to close about said article, the several sections aforesaid being provided with openings through which a finishing substance may pass in stenciling operations.

2. In masking apparatus of the class described, 5 in combination, a masking enclosure comprising a rearmost section, end sections, means normally holding the end sections in an open outward position, a frontward section movable in relation to the rearmost section, and members carried by the frontward section engageable with the end sections in moving the frontward section to closed position, whereby to cause the end sections to close to operative positions about an article of manufacture at the same time that the frontward section is caused to close about said article, the several sections aforesaid being provided with openings through which a finishing substance may pass in stenciling operations, 10 hinging means intermediate the frontward section and the rearmost section, standards for supporting the rearmost section, and hinging means between said standards and the end sections.

15 3. In masking apparatus of the class described, 20 in combination, a masking enclosure including a combination top and back section, spaced standards supporting said section in a stationary manner, a combined top and front section having the rearmost top portion thereof hinged to 25 the top portion of the combined back and top section, end sections mounted to move outwardly in reference to the above mentioned sections, means carried by the combined front and top section for engagement with the end sections to 30 cause the same to move to closed positions relatively to the other sections when the combined front and top section is moved to its closed position about an article of manufacture, and devices for causing the end sections to move outwardly 35 to open positions when the combined front and top section is raised to afford access to the article of manufacture enclosed in the said masking enclosure, the several sections being provided with openings to perform a stenciling function 40 in the application of a finish to an article enclosed by the masking enclosure.

4. In masking apparatus of the class described, 45 in combination, a masking enclosure comprising a rearmost section, end sections movably mounted upon said rearmost section, means normally holding the end sections in an open outward position, a frontward section movable in relation to the rearmost section, and members carried by the frontward section engageable with the end sections in moving the frontward section to closed position, whereby to cause the end sections to close to operative positions about an article of manufacture at the same time that the frontward section is caused to close about 50 said article, the several sections aforesaid being provided with openings through which a finishing substance may pass in stenciling operations, the means for holding the end sections in open position comprising springs, and counterbalancing means connected to the frontward section cooperative therewith to facilitate raising the same to open position and lowering the same to closed position.

5. In masking apparatus of the class described, 70 in combination, a masking enclosure comprising a rearmost section, a frontward section, standards supporting the rearmost section in a stationary manner, end sections pivoted to said standards and movable outwardly away from 75

each other, springs acting upon said end sections to normally pull them outwardly away from each other, and cam members on the forward section adapted to engage the end sections on downward closing movement of the front section to carry the end sections to closed positions by movement towards each other, the said several sections having openings for affording therein a stenciling function.

10 6. In masking apparatus of the class described, in combination, a masking enclosure comprising a forward section, a rearward section, standards supporting the rearward section in a stationary manner, movable connecting means intermediate the forward section and rearmost section, end sections, movable connecting means between the end sections and the said standards, devices carried by the forward section to operate with the end sections to cause the same 15 to move toward closed positions when the forward section moves toward a closed position about an enclosed article of manufacture, the said several sections having stenciling openings therein, and devices for causing the end sections 20 to move apart toward open positions when the forward section is raised toward an open position.

7. In masking apparatus of the class described, in combination, a masking enclosure comprising a rearmost section, a forward section, hinging means between the rearmost portion of the forward section and the forward portion of the rearmost section affording a horizontal hinging axis for enabling upward opening movement of 30 the forward section for access to an article disposed in the said enclosure, vertical standards supporting the rearmost section aforesaid, movable end sections disposed at the ends of the said rearmost and forward sections, and hinging 35 means at the rearmost portions of each of the end sections connecting the same to said vertical standards and enabling an outward swinging movement of the end sections, whereby to facilitate the removal of the article to be finished 40 in the masking apparatus, therefrom, when the forward section is elevated for such purpose.

8. Masking apparatus of the class described, in combination, a plurality of vertical standards, a masking enclosure comprising a rearmost section carried by said standards, a forward section hingedly connected at its upper portion with the forward portion of the rearmost section, whereby said forward section may be raised to obtain access to the article to be finished in 50 the masking enclosure, and end sections carried by the said vertical standards and projecting for-

wardly therefrom at the ends of the forward section and the rearmost section of the masking enclosure, the said several sections being provided with slots through which a paint or finish may be projected against the article within said enclosure. 5

9. Masking apparatus of the class described, in combination, a plurality of vertical standards, a masking enclosure comprising a rearmost section carried by said standards, a forward section hingedly connected at its upper portion with the forward portion of the rearmost section, whereby said forward section may be raised to obtain access to the article to be finished in 10 the masking enclosure, end sections carried by 15 the said vertical standards and projecting forwardly therefrom at the ends of the forward section and the rearmost section of the masking enclosure, the said several sections being provided with slots through which a paint or finish 20 may be projected against the article within said enclosure, a pair of uprights extending upwardly from the rear portion of the masking enclosure and provided with horizontal arms, pulleys carried by the arms of said uprights, flexible connections attached to the forward section and passing about the pulleys of said arms, and counterweights for said forward section connected to said flexible connections. 25

10. In masking apparatus of the class described, in combination, a pair of vertical standards, a masking enclosure including a back and top section supported by said vertical standards and projecting forwardly therefrom at its upper portion, a combined front and top section, 30 hinging means intermediate the uppermost portion of the front and top section and the uppermost portion of the back and top section so that the front and top section may be moved pivotally about the axis of said hinging means to elevate 35 and lower said front and top section, end sections at opposite ends of the above mentioned sections of the masking enclosure, and hinging means between the rearmost portions of the end sections and front portions of said vertical standards so 40 that the end sections may be moved outwardly and inwardly when the combined front and top section is moved upwardly and downwardly, respectively, to permit access to the article to be finished in the masking enclosure, and to cause 45 the sections to enclose said article, respectively, the various sections being provided with openings through which a finish may be projected onto the article disposed in the masking enclosure. 50

55 HARRY COHEN.
